ATTORNEY.

UNITED STATES PATENT OFFICE.

SAMUEL S. AMDURSKY, OF SYRACUSE, NEW YORK.

TUB-DRIP.

1,162,124.

Specification of Letters Patent. Patented Nov. 30, 1915.

Application filed June 1, 1915. Serial No. 31,559.

To all whom it may concern:

Be it known that I, SAMUEL S. AMDURSKY, a citizen of the United States of America, and a resident of Syracuse, in the county 5 of Onondaga, in the State of New York, have invented new and useful Improvements in Tub-Drips, of which the following, taken in connection with the accompanying drawings, is a full, clear, and exact description.

10 This invention relates to an attachment for gas, steam and other street mains whereby excessive accumulations of water of condensation, oil or other foreign matter in the mains may be withdrawn by suction, or the 15 quality or pressure of gas or steam may be tested from the surface of the street, and refers more particularly to the manner of connecting the suction or test pipes to the mains.

20 The main object is to enable these mains to be easily and quickly tested for accumulations of foreign matter, pressure or quality of the gas or steam passing therethrough without excessive opening of the main to 25 such an extent as to allow the escape of objectionable quantities of the fluid contained therein. Owing to the fact that these test tubes are placed under ground, they are more or less liable to become impaired or 30 clogged with sediment after a short period of use, and one of the important objects of my present invention is to connect such tubes to the main in sections through the medium of a bushing or coupling in such manner 35 that they may be removed in sections or as a unit as the operator may elect.

Another object, therefore, is to provide 40 means whereby the bushing and upper section may be secured together after being screw-connected so that the section which extends into the main may be removed simultaneously with the bushing and upper section by properly turning the upper section which is most easily available.

45 A still further object is to extend the bushing upwardly some distance above its screw connection with the upper section to better support the latter and relieve the threaded connection from excessive strains 50 and also to protect the threads from corroding elements which surround the bushing.

Other objects and uses will be brought out in the following description.

In the drawings—Figure 1 is an elevation, 55 partly in section, of a portion of a street main for gas or steam showing what is com-

monly known as a tub drip or trap and the test tube connected thereto. Fig. 2 is an enlarged sectional view of the bushing for connecting the inner and outer pipe sections to each other and to the head or top of the trap. Fig. 3 is an elevation, partly broken away, of the same bushing or coupling as applied directly to a steam or gas main showing a pressure gage on the outer 60 end thereof, the main being shown in section. 65

In order that my invention may be clearly understood, I have shown a gas or steam main—A—as provided with a tub drip or trap—A'—having its upper end closed by 70 a cap—a. This cap is provided with a relatively small threaded aperture—1—centrally in the upper side thereof for receiving a bushing—2—having its inner end threaded externally at—3—and internally at—4—75 and its intermediate portion threaded internally at—5—, while its outer end extends some distance beyond the threaded portion—5— and is provided with a circular opening—6—of smooth bore of substantially the same diameter as that of the threaded portion—5—, the portion 80 of the bushing between the end opening—6—and threaded portion—5—being chambered at—7—to lighten the bushing and to allow the annular flange as—6'—at the outer end to engage an upwardly projecting pipe which may be inserted therein some distance from its screw engagement 85 with the threaded portion—5—. 90

The externally threaded inner end of the bushing is screwed into the opening—1—, while the adjacent internally threaded portion—4— is engaged by the threaded end of a pipe—8—which extends downwardly into 95 the trap—A—some distance below the level of the main—A—to a point a short distance from the bottom of the trap.

A separate pipe—9—is inserted through the opening—6— and has its inner end threaded and engaged with the threaded portion—5—in which position it may be held by a set screw—10—entering a radially threaded aperture in the upper portion of the bushing between the threaded portion 100—5—and flange—6'—, thus permitting the bushing with the lower pipe section—8—to be removed upwardly by properly turning the upwardly extending pipe section—9. 105 This upper pipe extends to a point near the 110 surface of the ground and is normally closed by a cap—11— while the opening in the

pavement into which it projects may be closed by a surface cap or plate —12—.

In Fig. 3, I have shown the same bushing —2— as screwed into one side of a main —A— for receiving a relatively short pipe section —8'— having perforations communicating with the interior of said main, the upper pipe section as —9'— being provided with a cap —11'— to which may be connected a pressure gage —13— for testing the pressure of the gas or steam within the main.

What I claim is:

1. A street main having a relatively small threaded aperture in its upper side, a bushing having a reduced externally threaded end screwed into the aperture, said bushing having an internally threaded portion at its inner end and an additional internally threaded portion between its ends, and separate pipes screwed, respectively, into the internally threaded portions, one of the pipes extending into the main and the other pipe extending upwardly therefrom for cleaning or testing purposes.

2. A street main having a relatively small threaded aperture in its upper side, a bushing having a reduced externally threaded end screwed into the aperture, said bushing having an internally threaded portion at its inner end and an additional internally threaded portion between its ends, separate pipes screwed, respectively, into the internally threaded portions, one of the pipes extending into the main and the other pipe extending upwardly therefrom for cleaning or testing purposes, and means for securing the upwardly projecting pipe to the bushing, whereby the bushing and inner pipe may be unscrewed from the main by the turning of the upwardly projecting pipe.

3. A street main having a relatively small threaded aperture in its upper side, a bushing having a reduced externally threaded end screwed into the aperture, said bushing having an internally threaded portion at its inner end and an additional internally threaded portion between its ends, and separate pipes screwed, respectively, into the internally threaded portions, one of the pipes extending into the main and the other pipe extending upwardly therefrom for cleaning or testing purposes, the portion of the bushing at the outer end of the intermediate internally threaded portion being of smooth bore to allow the pipe to slide therethrough and serving to brace the upwardly project-

ing pipe at a point some distance upwardly from said intermediate internally threaded portion.

4. A street main having a tub drip provided with a relatively small opening in its top, a bushing threaded externally at one end and screwed into said opening, said bushing having its inner end and intermediate portion threaded internally and its outer end extended some distance beyond the intermediate internally threaded portion, separate pipes engaging the internal threads, one of the pipes extending into the main and the other pipe extending upwardly therefrom through the portion of the bushing above the intermediate internal threads, and means for locking the upwardly projecting pipe to the bushing, whereby the bushing and lower pipe may be removed from the main by turning the upper pipe, or by loosening the locking means permitting the upper pipe to be removed independently of the bushing and lower pipe.

5. A cleaning and testing attachment for street mains comprising a bushing having an externally threaded portion for attachment to the street main and separate internally threaded portions, separate co-axial pipes having adjacent threaded ends screwed, respectively, into the internally threaded portions, both pipes extending some distance beyond the corresponding ends of the bushing, one for entering the main and the other for cleaning or testing purposes.

6. A cleaning and testing attachment for street mains comprising a bushing having an externally threaded portion for attachment to the street main and separate internally threaded portions, separate co-axial pipes having adjacent threaded ends screwed, respectively, into the internally threaded portions, both pipes extending some distance beyond the corresponding ends of the bushing, one for entering the main and the other for cleaning or testing purposes, and means for locking the cleaning and testing pipe to the bushing, whereby the bushing and both pipes may be removed or reinserted as a unit by properly turning the cleaning and testing pipe.

In witness whereof I have hereunto set my hand this 24th day of May, 1915.

SAMUEL S. AMDURSKY.
